(57) **CLAIM**

The ornamental design for a screen with graphical user interface, as shown and described.

DESCRIPTION

FIG. 1 is a front view of a screen with graphical user interface showing the first image of the first embodiment of the claimed design;

FIG. 2 shows a second image thereof;

FIG. 3 shows a third image thereof;

FIG. 4 shows a fourth image thereof; and

FIG. 5 shows a fifth image thereof.

FIG. 6 is a front view of a screen with graphical user interface showing the first image of the second embodiment of the claimed design;

FIG. 7 shows a second image thereof;

FIG. 8 shows a third image thereof;

FIG. 9 shows a fourth image thereof; and,

FIG. 10 shows a fifth image thereof.

The appearance of the transitional image sequentially transitions between the images shown in FIGS. 1-5, as also shown in FIGS. 6-10. The process or period in which one image transitions to another image forms no part of the claimed design. The dotted, dot-dashed and dashed lines shown in the drawings show portions of the graphical user interface that form no part of the claimed design. The outermost broken line rectangle in FIGS. 1-10 shows the screen and forms no part of the claimed design.
